UNITED STATES PATENT OFFICE

PAUL GALENS, OF BROOKLYN, NEW YORK

WATER VEHICLE

Application filed January 21, 1930. Serial No. 422,367.

This invention relates to improvements in water vehicles and has particular reference to an aquatic appliance by which a bather may propel himself while in the water.

5 The primary object of the invention resides in a swimming device on which a person may lie in a prone position and by the manipulation of either hand, may actuate a propelling mechanism by which the device 10 will be driven over the surface of the water.

Another object of the invention is to provide a swimming device which is non-sinkable so as to be safe for use by persons who cannot swim and which may be used for 15 teaching such persons the art of swimming by giving them confidence while in the water.

A further object is the provision of a swimming device which is light in weight and which may be quickly taken apart for 20 convenient packing in a carrying case to enable the owner to carry the same to a beach or other water resort.

With these and other objects in view the 25 invention resides in certain novel construction, combination and arrangement of parts, the essential features of which are herein-after fully described, are particularly pointed out in the appended claims, and are illustrated in the accompanying drawings, in 30 which:

Figure 1 is a side elevational view of my improved swimming device in an assembled position.

Figure 2 is a top plan view of the same.

35 Figure 3 is a vertical transverse sectional view on the line 3—3 of Figure 1.

Figure 4 is a side elevational view showing the parts in a separated condition.

Referring to the drawings by reference 40 characters, the numeral 10 designates my improved swimming device in its entirely which includes a buoyant frame body 11 which is rectangular in plan when in a set up position, and which includes sections 45 12—12 and 13—13 which are respectively connected by hinges 14—14, the free ends of the front sections 12—12 being provided with inwardly extending portions 15—15 while the rear ends of the rear sections 13—13 are 50 connected by an end piece 16 hinged to the

respective sections 13—13 as at 17—17. The frame body when in a set up position is locked up together by hooks 18 which engage eyes 19. The inner edges of the portions 15—15 are provided with semi-circular recesses 20 which coact to provide a bearing for a vertically disposed shaft 21, the upper end of which carries a pulley wheel 22 and which shaft is locked in its bearing by a removable pin 23 which passes through the lower end of the shaft as shown in Figure 1 of the drawings. By removal of the pin 23, the shaft and pulley 22 may be removed for a purpose to be presently explained. Secured to the top of the pulley 22 is a handle member 24 by which an operator may manually apply rotation to the said pulley.

55 Detachably connected to the frame body 11 is a passenger carrying support 25 which includes a pair of spaced cross bars 26 to 60 which opposite ends of a flexible strip 27 is fixedly connected, the said bars 26 being provided with notches 28 which engage notches 29 in the side sections of the frame body 11, this construction being clearly shown in Figure 3 of the drawing. The cross bars 26 are securely held in position by hooks 28 pivoted to the sides of the frame body and which engage eyes 29 depending from the cross bar. 65 It will be seen that the passenger carrying support 25 may be separated from the frame body by unfastening the hook 28 and lifting the bars 26 from their engagement with the side walls of the frame body. In view of the fact that the strip 27 is flexible, the passenger support may be rolled into a compact bundle as illustrated in Figure 4 of the drawings.

70 Loops 30 are provided on opposite sides of the strip 27 for receiving split or openable rings 31 carried by pontoons 32 and which pontoons depend along opposite sides of the passenger support for preventing accidental capsizing of the device while in the water. By opening the rings 31 the pontoons 32 may be disconnected from the flexible strip 27 as 75 illustrated in Figure 4 of the drawings.

80 Secured to one of the forward rings 31 is a strap or belt 33, the opposite end of the belt being provided with a snap hook 34 for detachable engagement with the other front

ring 31 so that the said strip bridges the platform or passenger support 27 to enable an operator to be strapped thereon while lying in a prone position.

Bridging the side sections 13-13 adjacent the rear end thereof is a cross brace 35 provided with a bearing hanger 36 in alignment with a similar hanger 37 carried by the end wall 16 and 11 carried by the end wall 16 and which hangers removably support a propeller shaft 38, the same extending beyond the end wall 16 and which removably carries a propeller 39. Fixed to the propeller shaft 38 is a pinion gear 40 which is in constant mesh with a beveled gear 41 formed integral with a pulley 42, which pulley is mounted on a shaft 43 removably journaled in a bearing provided on the end wall 16. Encircling the pulley 42 and front pulley 22 is an endless belt 43 by which rotation may be imparted from the front pulley 22 to the rear pulley 42 for the purpose of turning the propeller shaft 38 and propeller 39. By mounting the driving assembly as shown and described, the same may be taken apart, as illustrated in Figure 4 of the drawings.

Extending rearward from the passenger supporting platform 25 is a propeller guard 43 which includes side bars 44 to which a flexible covering 45 is attached. The forward ends of the bars 44 are insertable in sockets provided in the rear cross bar 26 so as to render the guard 43 removable therefrom. This guard serves to prevent possible contact of the operator's legs or feet with the rotating propeller 39 when in a lying position upon the support 25.

When the device is set up for use as shown in Figures 1 to 3, inclusive, the same may be placed in the water and an operator by lying prone upon the support 25 may with either hand impart a turning movement to the pulley 22 by grasping the handle 24 and imparting rotation thereto. This rotation is imparted to the propeller driving mechanism through the endless belt 43 as previously mentioned, and which will of course turn the propeller 39 which moves the device forward over a body of water. It will be understood that forward and backward movement of the device is dependent upon the direction of rotation of the pulley 22.

Although no steering mechanism has been shown, it is possible for an operator to steer the device by placing his legs into the water as will be readily understood.

When not in use the parts may be separated as illustrated in Figure 4 of the drawing, and compactly placed in a case for carrying and transporting purpose. This feature permits of carrying the device to beaches and other water resorts where the same may be used. The parts are easy to assemble and which assembly may be performed by an unskilled mechanic.

Having thus described the invention, what I claim as new and desire to secure by Letters Patent is:-

1. A mechanical swimming device comprising an elongated buoyant body having a passenger carrying platform thereon, a pulley journaled forward of said body, a handle on said pulley, a propeller shaft journaled at the rear end of said body, a gear on said propeller shaft, a pulley journaled on said body at right angles to the axis of the propeller shaft, a pinion gear integral with said last mentioned pulley and in meshing engagement with said pinion gear, an endless belt passing around both of said pulleys, and a driving propeller carried by said propeller shaft. 70

2. A mechanical swimming device comprising an elongated buoyant body having a passenger carrying platform thereon, pontoons attached to opposite sides of said platform, a strap bridging said platform by which a person may be safely held thereon while in a lying position, a pulley journaled forward of said body, a handle on said pulley, a propeller shaft journaled at the rear end of said body, a gear on said propeller shaft, a pulley journaled on said body at right angles to the axis of the propeller shaft, a pinion gear integral with said last mentioned pulley and in meshing engagement with said pinion gear, an endless belt passing around both of said pulleys; and a driving propeller carried by said propeller shaft. 85

3. A swimming device comprising a buoyant elongated body frame, spaced cross bars bridging the sides of said body frame, a flexible strip secured to said cross bars and overlying said frame, pontoons carried by the sides of said flexible strip, a propeller shaft journaled in the rear of said body frame, and extending therefrom, a propeller mounted on said propeller shaft, and manually operable means operatively connected to said propeller shaft for imparting rotation thereto. 100

4. A swimming device comprising a buoyant elongated body frame, spaced cross bars bridging the sides of said body frame, a flexible strip secured to said cross bars and overlying said frame, pontoons carried by the sides of said flexible strip, a propeller shaft journaled in the rear of said body frame, and extending therefrom, a removable propeller guard coextensive with said strip for overlying said propeller, a propeller mounted on said propeller shaft, and manually operable means operatively connected to said propeller shaft for imparting rotation thereto. 115

5. A portable swimming device comprising a buoyant frame body consisting of a plurality of hingedly connected sections, hook and eye means for securing said sections in assembled position, a passenger carrying support removably mounted on said frame body including a flexible strip having cross 120

bars which fit into sets of notches provided in the sides of said frame body, means for fastening said cross bars to said frame body, pontoons removably connected to opposite sides of said passenger carrying support, a propeller shaft journaled at the rear of said frame body, a propeller mounted thereon, and manually operable means operatively connected to said propeller shaft for imparting rotation thereto.

10 6. A mechanical swimming device comprising a buoyant body, a hand operated pulley journalled forward of said body, a propeller shaft journalled rearward of said body, a propeller carried by said propeller shaft, a pulley journalled on said body at right angles to the axis of said propeller shaft, an endless belt passing around part of said pulleys, and power transmitting mechanism connecting said last mentioned pulley with said propeller shaft.

In testimony whereof I affix my signature.
PAUL GALENS.
